SHOE RACK

Walter Barnett, Leicester, England, assignor to
 United Shoe Machinery Corporation, Paterson, N. J., a corporation of New Jersey

Application February 15, 1936, Serial No. 64,083
 In Great Britain March 20, 1935

3 Claims. (Cl. 211—34)

This invention relates to racks such as are used for supporting shoes between operations performed upon the shoes during their manufacture.

5 In the use of shoe racks in carrying shoes from one part of a factory to another considerable difficulty has heretofore been experienced in preventing injury to shoes and particularly to those the uppers of which are constructed of light or delicate leathers or fabrics. This difficulty is due to the fact that the shoes may become displaced from the supporting members of the rack or may be subjected to jostling as the result of which the shoes come in contact with each other or 10 with portions of the rack in such a way as to scratch or otherwise mar the uppers.

In view of the foregoing, it is an object of the present invention to provide an improved shoe rack which is especially constructed and arranged 20 to carry shoes in such manner that the likelihood of injury thereto will be reduced to a minimum.

To this end and as illustrated, the invention provides a shoe rack in which the shoe-supporting portions thereof are composed of yielding 25 material and in which there is means securely to hold the shoes in position to prevent them from coming in contact with each other. Preferably, and as shown, the rack is provided with a shoe-supporting member comprising a shelf formed of sponge rubber having elongated openings extending therethrough and the walls of which are adapted closely to engage and to support the body portions of shoes carried bottoms up upon the shelf.

30 The construction above outlined is advantageous in that the shelf itself, being constructed of yielding material, will not offer such resistance to shoes as to mar them when they are placed in the rack or removed therefrom and, since the walls of the elongated openings are adapted closely to engage the shoes, the shoes will be firmly held upon the shelf with the result that adjacent shoes 35 will not touch each other.

These and other features of the invention will 40 be apparent from the following detailed description when taken in connection with the accompanying drawing and will be pointed out in the claims.

In the drawing,

45 Fig. 1 represents a perspective view of a portion of a shoe rack constructed in accordance with a preferred embodiment of my invention and showing a shelf with shoes in position thereon; and

50 Fig. 2 is a cross-section taken along line II—II of Fig. 1.

The shoe rack shown in the drawing comprises a frame composed of four vertical angle irons 10 having cross braces 12 upon which rests a shelf 14, it being understood that a plurality of such shelves may be mounted in the frame if desired. 5

The shelf 14 comprises a slab 16 of yieldable material, such as sponge rubber, which is mounted upon two rods 18 extending longitudinally of the rack and resting upon the end braces 12, the shelf being provided with a plurality of 10 shoe receiving openings 20. Preferably each of the openings 20 is formed in the shape of an oval which is wider at the rear of the shelf than at the front in order to correspond to the shape of a shoe placed in an opening bottom up with the 15 heel end of the shoe toward the rear of the rack. Preferably the openings are arranged in pairs with the spaces between the openings of each pair and between successive pairs of openings such that adjacent shoes will not engage 20 each other when in position in the openings. The walls of the openings, being yieldable, will readily conform closely to the contours of shoes of a wide range of sizes and shapes.

In order to protect the surface of the sponge 25 rubber against wear, and to protect delicate uppers from discoloration, the shelf is provided with a covering 22 conveniently of textile material such as swansdown or is sprayed with a coating of suitable material. In this connection it is to 30 be noted that the covering 22 extends over the body portion of the material 16, covers the walls of the openings 20 and also covers the exposed edge portions of the rods 18.

In the use of the rack, shoes such as indicated 35 at 24 are placed in position upon the rack by inserting them bottoms up, heel portions to the rear, in the openings 20, the material 16 of the shelf yielding sufficiently to permit the walls of the openings firmly to grip the shoes, thus to hold 40 them securely in position without, however, having any tendency to mar the shoes.

Having described my invention, what I claim as new and desire to secure by Letters Patent of the United States is:

45 1. A shoe rack comprising a support formed of relatively soft resilient material of appreciable thickness and having a plurality of elongated openings extending therethrough each for the reception of a shoe, the walls defining said openings being formed by the thickness of the material of said support thereby to engage and support the shoes over a substantial area, and said walls being yieldable to closely conform to the contours of shoes of different sizes and shapes. 55

2. A shoe rack comprising a support formed from relatively soft resilient material of appreciable thickness and having a plurality of elongated openings extending therethrough each for the reception of a shoe, a soft flexible covering enclosing said material and covering the side walls defining said openings, said side walls being formed by the thickness of said material and covering thereby to engage the shoes over a substantial area and readily to conform to the contours of shoes of different sizes and shapes.

3. A shoe rack comprising a relatively flat thick shelf of sponge rubber having a plurality of elongated openings extending therethrough, each adapted to receive a shoe, said shelf being of substantial thickness thereby to engage and support the shoes over a substantial area, and the marginal edges of said shelf about said openings being rounded to facilitate the insertion of shoes in said openings.

WALTER BARNETT. 10
